SYDNEY BEZZANT, OF BRISTOL, AND REGINALD BEZZANT, OF LONDON, ENGLAND.

ADJUSTABLE AND ATTACHABLE BOX COVER.

Application filed December 9, 1924, Serial No. 754,839, and in Great Britain December 13, 1923.

This invention relates to an adjustable and attachable box cover which may be used time after time in connection with any number of boxes of suitable size to keep dust 5 from sweets or other articles exposed for sale in boxes whilst leaving the goods visible to the public eye.

It is an object of the invention to provide a new or improved cover and other objects 10 are generally to provide a cheap and convenient device adapted to co-operate with a sweetmeat box or the like in the manner hereinafter described with reference to the accompanying drawings, and to afford the 15 combinations and arrangements of parts specifically claimed.

Referring to the drawings:

Fig. 1 is an isometric view of an attachable cover applied to a box, said cover being 20 slightly raised to give access to the interior of the box.

Fig. 2 is a similar view with the cover closed.

Fig. 3 shows the cover detached from the 25 box.

Fig. 4 shows an alternative form of cover.

As illustrated at Figs. 1, 2 and 3 the cover comprises a frame 1 in any metal, wood, ivorine, xylonite, horn or any suitable substance whatsoever which will hold a transparent surface 2 of glass, xylonite, whether flammable or non-flammable, or any other suitable transparent substance. Such frame may have superimposed on it, printed, embossed, enamelled, inlaid or in any manner whatsoever, suitable lettering, design or mark to identify or advertise, or describe goods or for any similar purpose, or same may be plain finished.

Secured to the frame is an elastic band 3 or bands so arranged that when clasped around any box 4 the ordinary cover 5 of which may remain open or be removed, the cover provides a protection from dust, flies, etc., whilst the contents remain visible and in a hygienic condition.

In the case of ordinary wooden or general trade sweet or chocolate boxes one elastic band usually would be used which would

enable the adjustable cover to be lifted 50 against the junction between the box and its ordinary cover as pivot to remove the required portion of the contents, the secondary or adjustable cover then returning almost automatically to its original position owing 55 to the elasticity of the band 3. In the case of larger boxes of fruits, etc., where the adjustable cover would not be required to be frequently lifted a further elastic band towards the other end of the frame would be 60 desirable. Ribbons from the frame in the form of a band for decorative purposes may be used or a band of wire or of any material or metal whatsoever in the form of a spring or otherwise such addition being merely an 65 elaboration of the root idea.

At Fig. 4 is illustrated a form where a thick glass is used or a xylonite or transparent substance 2 of such thickness or stability that same may be drilled at the edges 70 or surface to allow the fixing of the band in any manner whatsoever, the use of same in the manner described being a suitable substitute for the frame surface holder and forming part of this invention.

The elastic may be fastened to the frame by slot, knot, pressure, device such as a hook, thickness such as a thickened end after being passed through slot, or in any manner whatsoever which accomplish the purpose 80 of providing the necessary band for the purpose in view.

We claim:

For use in combination with a box having a hinged lid, a transparent cover member 85 having an edge adapted to lie against said lid when the said lid is opened and an expandable band adapted to encircle said box adjacent said edge and to serve both to retain said cover member normally shut and 90 to press its said edge against said lid to form a pivot upon the raising of said cover member.

In testimony whereof they affix their signatures.

SYDNEY BEZZANT.
REGINALD BEZZANT.
